UNITED STATES PATENT OFFICE.

CHARLES W. McGONIGLE, OF WALLA WALLA, WASHINGTON, ASSIGNOR OF ONE-FOURTH TO LARS H. LARSON AND ONE-FOURTH TO JOHN SAWBRIDGE, OF NORTH YAKIMA, WASHINGTON.

PUMP.

No. 805,318.

Specification of Letters Patent.

Patented Nov. 21, 1905.

Application filed March 24, 1905. Serial No. 251,823.

To all whom it may concern:

Be it known that I, CHARLES W. McGONIGLE, a citizen of the United States, residing at Walla Walla, in the county of Walla Walla and State of Washington, have invented a new and useful Pump, of which the following is a specification.

This invention relates to mechanism of that class employed for the pumping of liquids, and has for its principal object to utilize the pressure exerted by an explosion of gas or a gaseous compound for the purpose of driving a body of liquid from a pumping-chamber and afterward utilizing the vacuum created by the condensation of such gases in again filling the chamber with water preparatory to a second explosion, the mechanism being of such character that when once set into operation the pumping will continue so long as fuel is supplied thereto.

A further object of the invention is to provide a pumping mechanism of the character described in which the explosive mixture is admitted to the pumping-chamber and exploded at the proper time, both operations being controlled by a float so arranged that when the proper volume of water has entered the chamber the explosion will occur and a definite quantity of liquid will be expelled from the chamber, a further object in this connection being to provide means whereby a portion of the exploded gases or products of combustion may be allowed to escape from the chamber in order that the remaining gases may be quickly condensed to form a partial vacuum.

A still further object of the invention is to provide improved means for controlling the quantity of fuel, either crude or refined oil, admitted to the chamber and to insure the delivery of exactly the same quantity of fuel at each operation.

A still further object of the invention is to provide a simple and economical form of vaporizing apparatus in which the fuel in liquid form may be vaporized and more readily intermingled with the air to produce the explosive compound.

A still further object of the invention is to provide a pumping mechanism in which provision is made for permitting the escape of excess air from the air chamber or bell, so

that the operation of the pump may be made uniform.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size, and minor details of the structure may be made without departing from the spirit or sacrificing any of the advantages of the invention. 65

In the accompanying drawings, Figure 1 is a vertical sectional view of a pumping mechanism constructed in accordance with the invention. Fig. 2 is a detail sectional view of the fuel-injector. Fig. 3 is a sectional elevation drawn to an enlarged scale and on a plane at a right angle to the mechanism as shown in Fig. 1, illustrating particularly the valves for the admission of air and the igniting-flame to the pumping-chamber. Fig. 4 is a detail perspective view of the valve for controlling the admission of air to the pumping-chamber. Fig. 5 is a sectional plan view of said valve. Fig. 6 is a view similar to Fig. 1, illustrating a slightly-modified construction of pump. 80

Similar numerals of reference are employed to indicate corresponding parts throughout the several figures of the drawings.

The apparatus forming the subject of the present invention is designed as a cheap and efficient substitute for the ordinary type of piston or plunger pumps, and in its simplest form includes means for admitting an explosive compound to a water-containing chamber and for igniting the compound, so that the force of explosion may force the water from the chamber, the gases on condensing creating a partial vacuum within the chamber and a fresh volume of water being introduced thereto under atmospheric pressure. 95

The pumping-chamber 10 is preferably in the form of an upright cylinder and at its lower end communicates with an air-chamber, suitable one-way valves 12 being introduced between the chambers to prevent the backflow of the fluid to the chamber 10. Leading into the lower portion of the chamber 10 is a suction inlet-pipe 13, having a suitable controlling-valve 14, and one-way valves 15 are employed

to prevent the backflow of water from the chamber to the pipe. From the lower portion of the air-chamber 11 leads an educt-pipe 17, through which the water is forced to any desired point. In the lower portion of the chamber 10 is a dash-pot 18, arranged for the reception of a float 19, that fits rather loosely within the dash-pot, and the bottom of the dash-pot has an opening 20, through which the water or other liquid may enter. This float is so arranged that it will not be raised by the water until the latter has nearly reached the level at which the explosion is to occur, and when this level is reached the float will move up quickly and will effect in successive order the entrance of the charge of fuel, the volume of air necessary to intermingle with the fluid to form an explosive compound, and the igniting of the mixture, so that the explosion cannot occur prematurely or until the desired volume of water has been admitted to the chamber.

At one side of the chamber is a vaporizing apparatus, preferably in the form of a pair of concentric cylinders 20 and 21, the cylinder 20 opening at the outside of the casing and the cylinder 21 having an open end facing the interior of the casing or pumping chamber. The inner and smaller cylinder 21 forms a retort into which the charge of liquid fuel is injected, and said retort is constantly heated by a burner 22 of any ordinary construction, said burner being connected by pipes 23 and 24 to a tank 25, containing gasoline, crude oil, or other liquid fuel.

The inner cylinder is provided with a port 27, that is normally closed by a valve 28, carried by a slidably-mounted stem 29, that is adapted to suitable brackets 30 within the pumping-chamber, and said valve is normally held to its seat by a counterweighted lever 31, pivoted on a suitable supporting-bracket 32. The lever 31 is provided with an upwardly-extending and curved tappet-arm 33, with which may engage a suitable valve-operating arm 34.

At a point below the horizontal plane of the retort the casing is provided with an air-inlet opening 36, that is normally closed by a slidably-mounted valve 37. This valve is wedge-shaped in form, its outer inclined edge being supported by a pair of correspondingly-inclined arms 38, that are spaced from each other to permit the passage of a lug 39, carried by the valve, and when the valve is allowed to move down by gravity its inclined face bearing against the inclined arms 38 will force said valve tightly to its seat and effectually close the air-entrance opening 36.

To the top of the float is connected one end of a lever 38', the opposite end of which is pivoted to a bracket 39', carried by the inner wall of the chamber, and pivotally connected to this lever is an arm 40, having a lug 41 for engagement with the lug 39, so that when the

float is moved upward the two lugs will engage and the air-valve will be opened to admit the quantity of air necessary to mingle with the gas in the formation of an explosive compound. The arm 40 is continued upward and is pivotally connected to the tappet-arm 34, the connection between the two being such that the arm 34 may yield in but one direction, and during upward movement of the arm it will engage with the tappet-arm 34 to momentarily open the valve 28, and thus explode the gases in the retort by contact with the flame of the vaporizing-burner, after which the arm will pass up beyond the arm 33, and on downward movement of the float the arm will yield to permit its ready passage below the tappet 33, it being understood that the opening of the valve 28 is but momentary, said valve instantly closing under the action of the counterweighted lever 31.

At a point diametrically opposite the vaporizer 21 is a fuel-injecting nozzle 43, which is in communication with the tank 25 through the medium of the pipe 24, the flow of oil from the nozzle being normally prevented by a valve 45, adapted to a suitable seat within the nozzle. This valve is carried by a suitably-guided stem 46, having at one end an enlarged head 47, and between the guide and head is a helical compression-spring 48, that tends normally to hold the valve in its closed position. The outer portion of the nozzle is extended to form a cylinder 50, having at one end a stuffing-box 51, through which extends a combined plunger and valve 52. The outer portion of the plunger is threaded and extends through an opening formed in a guiding-bracket 58, and on the threaded portion of the plunger is a nut 59, between which and the stuffing-box is arranged a compression-spring 60, tending normally to maintain the plunger in the position shown in Fig. 2, so that the space between the valve 45 and the pipe 24 may be filled with liquid fuel from the tank 25. By suitably adjusting the nut 59 the front end of the plunger may be moved in or out for some distance and increase or decrease the quantity of fuel admitted to the pumping-cylinder. To the rear end of the plunger is connected a stem 61, the rear end of which fits within a suitable opening in a guiding-bracket 62, and said stem is threaded for the reception of a pair of adjustable nuts 63, with which engages a lever 64', that is moved by the upper end of an operating-lever 64, fulcrumed to a bracket 65, projecting from one side of the chamber. The lower end of the lever 64 is connected by a link 65' to one arm of a bell-crank lever 66, arranged within the lower portion of the pumping-chamber, the opposite arm of said bell-crank lever being connected to a stem 67, depending from the float 19. It is obvious that when the float is elevated the upper portion of the lever 64 will be moved inward, and by engagement

with the nut 63 or with an intervening lever 64' the plunger will be moved forward and will eject from the nozzle a certain quantity of liquid fuel, the quantity depending on the extent of movement of said plunger, and this may be regulated by proper adjustment of the nut 63. When the plunger moves forward, it will first engage with the head 47 of the valve-stem and will open the valve to permit the free passage of the fuel, the latter being ejected directly into the retort space 21 and instantly transformed into vapor and intermingled with the air previously admitted by the opening of valve 37.

5 Near the lower portion of the pumping-chamber is arranged a port 68 for permitting the exhaust of a portion of the exploded gases or products of combustion immediately after each active pumping operation. This port is normally closed by a valve 69, that is provided with a projecting stem 70, and in alinement with but separated from the stem is a stationary lug 71. Projecting from the casing are guides for the reception of a vertically-movable rod 72, having a wedge-shape upper end that may be forced between the end of the stem 70 and the lug 71, the parts being normally held in this position by a coiled compression-spring 73, so that the valve cannot be opened under the force of the explosion.

Near the lower end of the float 19 is an annular groove 75, the walls of which are inclined or rounded, and said groove is adapted to receive a slideable rod 76, that normally is pressed into engagement with the groove by a leaf-spring 77. This rod serves as a retarding means for holding the float in its lowest position until the water has reached a certain level and overcomes the resistance offered by said rod. The rod 76 extends outside the wall of the pumping-chamber and is provided with an inclined arm 78, adapted to engage and exercise a camming effect on a projecting pin 79, carried by the vertically-movable rod 72. When the float moves upward, the rod will ride out of the annular groove, and the inclined arm acting on pin 79 will depress the latter until its wedge-shape end is free from contact with the stem 70 and lug 71, whereupon the valve 69 is free to open; but at this time the valve will be held closed by atmospheric pressure, owing to the partial vacuum within the pumping-chamber. Immediately after the bottom of the float passes beyond the rod the spring 73 will elevate the rod 72 and the valve will be again locked in place.

In the upper portion of the pumping-chamber is a sparking plug 82, that is connected in circuit with a battery and sparking coil 83, of any ordinary construction, and in the circuit is a manually-operable circuit-closer 84, by which the sparking circuit may be established once or twice at the beginning of operations; but after that the operation of the pump will be entirely automatic.

At the top of the pumping-chamber is an ordinary form of safety-valve 85, which may be held to its seat by a counterweight or spring.

In the operation of the parts thus far described the explosive charge is admitted to the pumping-chamber and is exploded by closing the circuit of the sparking plug. The air within the chamber is driven out through the check-valves 12 to the chamber 11, and when the products of combustion have condensed a partial vacuum will be formed within the pumping-chamber, so that water or other fluid will enter through the suction inlet-pipe 13 under atmospheric pressure, the water flowing up into the pumping-chamber until the float 19 is almost submerged. The buoyancy of the float then overcomes the resistance offered by the rod 64, which acts in the nature of a restoring means, and as the float is elevated the air-valve is opened, admitting a quantity of air, and the plunger 52 is operated to force a charge of gasolene or other liquid fuel into the retort 21. The vapor from the liquid fuel and the air commingle to form an explosive compound, and this charge is ignited by the opening of the valve 28. When the explosion occurs, the water or other fluid within the chamber 10 will be forced past the check-valves 12 into the air-chamber 11, and during the outflow of water the float 19 will gradually descend, this movement to some extent being retarded by the dash-pot 18. When the lower end of the float strikes the rod 76, the latter will be moved outward and its cam-like arm 78 will depress the rod 73, so that the port 68 will be opened under the pressure of the exploded gases and a portion of the products of combustion will escape to the atmosphere. This operation occurs very quickly and the float in continuing to move down will again present its groove in alinement with the rod 76, so that the port will be again closed, leaving within the chamber a comparatively small quantity of exploded gases. These gases will quickly condense, and a partial vacuum will be formed within the chamber, so that water will again flow thereinto under atmospheric pressure, and the operation will continue as before.

The air-chamber 11 is provided with a port 89, that is closed by a float-valve 90. This port permits the escape of any excess air in the chamber, but is closed as soon as the water elevates the float, and thereafter the volume of air above the level of water is compressed and serves after the explosion of the charge to force the water from the chamber out through the discharge-pipe 17.

In Fig. 6 is illustrated a slight modification, wherein electromagnetically-controlled operating devices are employed for effecting the several operations. In this case the construction of the fuel-injector is the same as that previously described with the exception that

the operating-lever 64^a is in the form of an armature arranged within the field of force of an electromagnet 92. This electromagnet is connected in a circuit including a revoluble 5 circuit-closer 93, mounted in suitable bearings in the upper portion of the casing and having a projecting lug 94 for contact with a lug 95, carried by a vertically-movable stem 96, the lower end of which is secured to a float 97 10 within the chamber. The movable contact member 93 is provided with a counterweight 98, that serves to return the same to an initial position immediately after each operation. The float rod or stem 96 is further provided 15 with a contact 99, arranged to engage a stationary spring-contact 100, that is in circuit with an electromagnet 101, arranged near the lower portion of the casing. When the electromagnet 101 is energized, it attracts an 20 armature 102, carried by the lower end of a pivotally-mounted valve-operating lever 103, that is provided at one end with a valve 104, controlling an air-entrance port 105 in the casing. In the upper portion of the chamber 25 is a spark-plug 106 in circuit with a sparking coil 107, and the terminals of the circuit are connected to a contact 109 and the armature-lever 103, respectively. Contact 109 is normally engaged by a spring-pressed contact 30 110 to complete the circuit of the electromagnets 101. The contact 110 is arranged in the path of movement of a block of insulating material 112, carried by the armature-lever 103, and when the latter is moved in- 35 ward under the influence of the electromagnet the block will engage contact 110 and will move the same from contact 109, and at the same time a small lug 113, carried by the armature-lever, will engage said contact 109 40 and close the sparking circuit. In the operation of this mechanism the float will be elevated by the water until lug 95, wiping past the lug 94, closes the circuit of the electromagnet 92 and operates the plunger to in- 45 ject the liquid fuel into the vaporizer. As lug 95 rides past the lug 94 the revoluble contact 93 will be restored to its initial position by the counterweight. On continuing the upward movement of the float contact 99 will 50 engage contact 100, and thereupon the circuit of the electromagnets 101 will be completed and the armature 102 will be attracted, thus opening the valve 104 and allowing a sufficient quantity of air to enter the pumping- 55 chamber to commingle with the vapor and form an explosive compound. The movement of the armature-lever forces the block 112 against spring-contact 110, thus breaking the circuit of the electromagnet 101 and es- 60 tablishing the sparking circuit, the operations being carried on in successive order and so rapidly that only a small volume of air will be admitted to the pumping-chamber.

In order to prevent the valve 104 opening 65 after condensation of gases within the pump-

ing-chamber, a lock 112' is preferably employed, said lock being connected to a suitable float 113', which will maintain the valve in closed position until the water has reached a predetermined level.

With an apparatus of this class the ordinary plunger-operated pumping mechanisms may be dispensed with and large volumes of water may be raised at a minimum expense to any desired height. The mechanism, moreover, is of such character as to require practically no attention after the proper adjustment of the parts has been effected.

Having thus described the invention, what is claimed is—

1. In pumping mechanism, a pumping-chamber, liquid inlet and discharge openings, means for admitting an explosive charge thereto, a float-controlled means for igniting the charge, and means for retarding the movement of the float.

2. In pumping mechanism, a pumping-chamber having liquid inlet and discharge openings, means for admitting an explosive charge to the chamber, means for igniting the charge, a float for controlling the operation of the igniting means, and mechanism for retarding the movement of the float until the liquid has reached a predetermined level.

3. In pumping mechanism, a chamber having liquid inlet and discharge openings, means for admitting an explosive charge to the chamber, means for igniting the charge, and a float for controlling the operation of the explosive-charge inlet and igniting means.

4. In pumping mechanism, a pumping-chamber having liquid inlet and discharge openings, a fluid-fuel injector, a float for operating the same, a vaporizer into which the fuel is injected, means controlled by the float for admitting air into the chamber, and means controlled by the float for igniting the explosive charge.

5. In a pumping mechanism, the combination with a chamber having inlet and discharge openings, of a float, means normally restraining the float until the water has reached a predetermined level, a fluid-fuel injector controlled by the float, a vaporizer for the fluid fuel, an air-inlet controlled by the float, and an igniting device also controlled by the float.

6. In a pumping mechanism, the combination with a chamber having liquid inlet and discharge openings, of a normally restrained float, a fluid-fuel inlet, an air-inlet, and an igniting device, and means for connecting all of such mechanism to the float, whereby on upward movement of the latter the fuel will be injected, the air admitted, and the charge exploded in successive order.

7. In a pumping mechanism, the combination with a chamber having liquid inlet and outlet openings, of a nozzle for injecting fluid fuel into the chamber, a supply-tank connected to the nozzle, a spring-closed valve for the

nozzle, a plunger arranged in the rear portion of the nozzle, means for adjusting the position of the plunger, and a float arranged within the chamber and to which said plunger is connected.

8. In pumping mechanism, the combination with a pumping-chamber having liquid inlet and outlet openings, of an injecting-nozzle having a spring-closed valve, a tank to which said nozzle is connected, a plunger arranged within the rear end of the nozzle, a spring tending to restore the plunger to the normally open position and permit closing movement of the valve, and a float arranged within the chamber and to which said plunger is connected, whereby on upward movement the plunger and valve will be opened, and a predetermined quantity of fuel will be forced through the nozzle.

9. In a pumping mechanism, the combination with a chamber having liquid inlet and discharge openings, of a fluid-fuel-injecting nozzle, a pipe connecting the same to a source of fuel-supply, a spring-closed valve in the nozzle, a plunger mounted on the rear portion of the nozzle, a threaded stem carried by the plunger, nuts adjustable on the stem, a float, and a lever mechanism connected to the float and adapted to make contact with said nuts, and thereby force the plunger forward within the nozzle to open the valve and discharge a predetermined quantity of fuel from the nozzle.

10. In a pumping mechanism, the combination with a pumping-chamber having liquid inlet and outlet openings, of a fluid-fuel injector, a vaporizer disposed in alignment with the injector, and in the form of an inwardly-projecting open-ended cylinder, means for admitting air to the chamber to mingle with the vapor, means for igniting the explosive charge, and a float for controlling the operation of said mechanisms.

11. In a pumping mechanism, the combination with a chamber having liquid inlet and outlet openings, a fluid-fuel injector, an air-port, a pair of inclined arms adjacent thereto, a wedge-shaped valve slidable between said arms, and the wall of the chamber and serving to close said port, a lug projecting from the valve, and a float operatively connected to said lug.

12. In a pumping mechanism, the combination with a pumping-chamber, having liquid inlet and outlet openings, of means for admit-

ting an explosive charge to the upper portion of the chamber, means for exploding the charge, a normally locked valve for controlling the exhaust of a portion of the products of combustion, and a float for locking and unlocking said valve.

13. In a pumping-mechanism, the combination with a pumping-chamber having liquid inlet and outlet openings, of means for admitting an explosive charge to the upper portion of the chamber, an igniting means, an exhaust-port for a portion of the products of combustion, a valve normally closing said port, a locking-rod for the valve, an inclined arm forming a cam for engagement with said rod, and a float having a recess or groove for engaging the end of the rod to effect locking and unlocking of said valve.

14. In a pumping mechanism of the class described, the combination with a pumping-chamber having fluid inlet and outlet openings, of a dash-pot disposed within the chamber and having an opening at its lower end, a float arranged within the dash-pot, a float-restraining means, means for admitting an explosive charge to the upper portion of the chamber, means for igniting said charge, and means connecting the float to the explosive-charge-inlet devices, the dash-pot and restraining means serving to retard movement of the float in both directions.

15. In mechanism of the class described, the combination with a pumping-chamber having inlet and discharge openings, of a dash-pot disposed within the chamber, a float within the dash-pot, said float being provided with a groove or recess having tapered walls, a fluid-fuel injector, an air-port, a valve controlling the same, means for connecting the fluid-fuel injector and valve to the float, a valve for controlling the exhaust of a portion of the products of combustion, a stem on said valve, a spring-pressed locking-rod for engaging the stem and provided with a pin or lug, and a rod arranged to engage the groove or recess and provided with a cam-shaped portion to engage with said lug.

In testimony that I claim the foregoing as my own I have hereto affixed my signature in the presence of two witnesses.

CHAS. W. McGONIGLE.
